W. Bailey
J. M. Poor

UNITED STATES PATENT OFFICE.

MORTON TOWER, OF BOSTON, MASSACHUSETTS.

DESIGN FOR CAR BASKET-RACKS.

Specification forming part of Design No. 5,145, dated July 25, 1871.

To all whom it may concern:

Be it known that I, MORTON TOWER, of Boston, in the county of Suffolk and Commonwealth of Massachusetts, have originated a new and pleasing Design for the End Bracket of Car Basket-Racks, of which the following specification is a description and the accompanying drawing a representation.

My present design relates to the figured ornamental end brackets or supports of a car basket-rack, so called, or those devices applied to the walls of railway carriages to contain the parcels of passengers, the said design consisting, in addition to these brackets, of a medallion ornament, whereby a rich and unique appearance is imparted not only to the immediate object to which it

is applied, but to the interior of the car containing the racks.

The accompanying drawing exhibits, at A, the ornamental end support or bracket of a basket-rack, and at B a medallion added to about the center thereof.

In practice the bracket is usually bronzed and the medallion plated with nickel and burnished.

I claim—

The herein-described design for the brackets of car basket-racks.

MORTON TOWER.

Witnesses:

M. BAILEY,
C. B. NOTTINGHAM.
